UNITED STATES PATENT OFFICE

FREDERICK HEATH, OF TACOMA, WASHINGTON.

HOLLOW CORNER-BLOCK

1,294,905.

Specification of Letters Patent. Patented Feb. 18, 1919.

Application filed November 1, 1916. Serial No. 128,918.

To all whom it may concern:

Be it known that I, FREDERICK HEATH, a citizen of the United States, and a resident of Tacoma, in the county of Pierce and State of Washington, have invented a certain new and useful Improvement in Hollow Corner-Blocks, of which the following is a specification.

My invention relates to improvements in hollow corner blocks for use in hollow wall construction, and it consists in the combinations and arrangements herein described and claimed.

An object of my invention is to form a hollow building block for constructing corners of walls, jambs of openings, and for building piers, which will give a greater strength when built in a wall than the ordinary corner block now used.

A further object of my invention is to provide a corner block which not only has great strength but when placed in position will make a more slightly corner than other blocks in common use.

Other objects and advantages will appear in the following specification, and the novel features of the invention will be particularly pointed out in the appended claims.

My invention is illustrated in the accompanying drawings forming part of this specification, in which—

Figure 1 is a perspective view showing a wall constructed with corner blocks which form the subject of the present application, one of said blocks being shown in section, and

Fig. 2 is an enlarged section along the line 2—2 of Fig. 1.

In carrying out my invention I make a corner block having the longitudinal webs 1, 2, and 3, respectively, the transverse webs 4 and 5, and a diagonal web 6 formed integrally with the other webs. A top 7 and a bottom 8 are provided, as shown in Fig. 2.

In joining a wall the corner blocks, which I have designated in general by C, are placed as shown in Fig. 1. It will be noticed that these blocks are contiguous to the blocks A and B, the blocks A adjoining the open ends of the corner blocks C so that the

webs 1, 2, and 3 are in alinement with the webs of the blocks A, while the blocks B abut the sides of the corner blocks C, so that the webs of the blocks B are in alinement with the webs 4 and 5 of the corner blocks. 55

As will be noted, each corner block has one closed end which is formed by the web 4.

By constructing a corner block in this manner, corners can be made which are just as strong as any other part of the wall. These 60 corner blocks, as has been pointed out, will bond in with the ordinary wall tiles or blocks. Instead of having a corner course at the corner or angle, there is a web 6 which binds the webs of the corner blocks together 65 and makes a very strong construction. This obviates the necessity of having a mortar joint, as where the corner blocks are mitered, and it also obviates the necessity of weakening the wall as where the blocks are placed 70 on end.

While I have shown the corner block as having two voids, it will be understood that one, two, or more voids may be used without departing from the invention. 75

The blocks may be made of any suitable material, such as clay, plaster product, cement, etc., and they may also be of any desired sizes.

I claim:—

1. A hollow corner block having a horizontal top and a horizontal bottom, a plurality of vertically extending parallel webs spaced apart and joining the top and the bottom, one of said webs forming a continuous side, another of said webs forming a side portion and terminating short of the end of the block, a second set of vertically extending parallel webs disposed at right angles to said first named webs, one of said second 80 named set of webs constituting an end of the block, and a diagonal vertically extending web joining the points of intersection of said angularly disposed webs and the end of the shorter side web. 85

2. A hollow corner block having a horizontal top and a horizontal bottom, a plurality of vertically extending parallel webs spaced apart and joining the top and the bottom, one of said webs forming a con- 100

tinuous side, another of said webs forming a side portion and terminating short of the end of the block, a second set of vertically extending parallel webs disposed at right angles to said first named webs, one of said 5 second named set of webs constituting an end of the block, a diagonal vertically ex-

tending web joining the points of intersection of said angularly disposed webs and the end of the shorter side web, the distance between the end of the side web and the end web being equal to the width of the block. 10

FREDERICK HEATH.
